UNITED STATES PATENT OFFICE.

FRANK A. RYTHER, OF CHICAGO, ILLINOIS.

BUCKLE.

1,257,028.

Specification of Letters Patent. Patented Feb. 19, 1918.

Application filed March 8, 1917. Serial No. 153,419.

To all whom it may concern:

Be it known that I, FRANK A. RYTHER, a citizen of the United States, residing at Chicago, in the county of Cook and State of Illinois, have invented certain new and useful Improvements in Buckles; and I do declare the following to be a full, clear, and exact description of the invention, such as will enable others skilled in the art to which it appertains to make and use the same.

My invention relates to buckles and aims to provide a novel buckle devoid of the usual tongue for eliminating the use of holes or apertures in the strap secured thereby.

An object of my invention is to provide a buckle of this character in which a strap is secured thereto without the use of any rivets or stitching or other fastening means employed in the present day type.

A further object is to provide a buckle of this character which is easily operated, cheap to manufacture and produces the best results with a minimum of wear in the parts thereof.

A still further object of my invention is to produce a buckle to which the strap is secured by means of a keeper designed also to act as a retainer for the free end of the strap.

With these and other objects in view, my invention resides in the novel construction and combination of parts to be hereinafter described and claimed.

In the accompanying drawings, like reference numerals designate similar parts.

Figure 1 is a plan view of my buckle;

Fig. 2 is a vertical longitudinal central section on the line 2—2 of Fig. 1;

Fig. 3 is a similar view showing the buckle previous to being clamped; and

Fig. 4 is a transverse vertical section on the line 4—4 of Fig. 3.

In this preferred form, my buckle consists of a substantially U-shaped frame having a base 1 and arms 2. These arms 2 converge toward each other for a portion of their length and are then continued parallel to the end of the frame. Extending transversely between the arms 2 of the frame at the inner end of the parallel portion of the arms 2 is a bar 4 its width in cross section being equal to one-half the width of the arms 2 to which it is secured. This bar 4 rises from the bottom edge of the frame and has one face thereof slanting downwardly in the direction of the open

end of the U-shaped frame. This slanting face 5 is provided with a channel 6 extending throughout its length for a purpose to be hereinafter described.

Between the outer ends of the arms 2 is mounted a transverse shaft 9 which has pivotally mounted thereon a cam lever 8. This lever 8 is provided with a curved handle portion 16 for a purpose to be described. The lower end of the lever 8 is formed with a cam-shaped surface 10 having serrations 11 thereon. This cam surface extends between the arms 2 and is eccentrically mounted therebetween on the shaft 9. This cam surface 10 is located on the under side of the lever 8 which is provided on its opposite side with lugs 17 adjacent the arms 2 of the frame adapted to receive the shaft 9 therethrough to form a pivotal mounting for the lever 8.

The base 1 of the frame is provided with a rectangular aperture 7 extending therethrough. The inwardly converging portions of the arms 2 provide an enlarged space 3 adjacent the end 1 of the buckle. A substantially rectangular looped keeper 15 is adapted to be disposed in this enlarged space 3 with its end surfaces 18 in engagement with the walls 2 to retain the keeper therebetween. This keeper serves to firmly secure the strap 12 to the end 1 of the buckle and is extended above the frame of the buckle to receive the free end 19 of the strap thereunder when the strap has been passed between the bar 4 and the cam lever 8 at the opposite end of the buckle.

The keeper 15 is disposed in the space 3 adjacent the end 1 of the buckle and the strap 12 is then inserted through the aperture 7 in the end 1, folded around the lower bar of the keeper 15 and extended back upon itself through the aperture 7 and terminates beyond the end 1. By this construction the lower bar of the keeper 15 will act as a wedge to secure the strap 12 to the buckle. Owing to the contact of the sides 18 of the keeper 15 with the walls 2 of the buckle frame, the keeper is retained within the frame and prevented from becoming disengaged. The upper bar of the keeper is elevated above the top of the buckle frame and acts as a retainer for the loose portion of the free end of the strap after it has been passed through the clamp comprising the lever 8 and the bar 4. The free end of the strap 12 is inserted between the cam sur-

face 10 and the slanting face 5 of the bar 4 from the underside of the buckle frame and is drawn upwardly and beneath the elevated bar of the keeper 15 to its desired adjustment. The lever 8 is then pressed down against the surface of the strap which will cause the cam surface carrying the serrations 11 to bite into the strap and force the same against the channeled face 5 of the bar 4 which will hold the strap in secured position.

It will be seen that any movement of the strap in a direction opposite to that in which it is pulled for fastening will cause the cam carrying the serrations 11 to bite more firmly into the strap and further compress it against the bar 4 and into the channeled portion 6, thereby forming an absolute lock for the strap.

It is to be understood that I do not limit myself specifically to the particular form as shown and described herein as it will be obvious that minor details of construction may be made without changing the merits of the invention.

Copies of this patent may be obtained for five cents each, by addressing the "Commissioner of Patents, Washington, D. C."

What I desire to protect by Letters-Patent and claim is:—

A device of the class described comprising a U-shaped frame having base and side arms, said arms being parallel substantially midway their length and having their remaining portion flared outwardly, the base of said frame having a rectangular opening cut therein, a rectangular link positioned between the flared portions of the side arms, the end of the strap being passed through the opening and around the lower portion of said link and out again through said opening, thereby holding the link in position, the upper portion of said link receiving the other end of the strap and clamping means at the other end of the frame to hold the strap in secured position.

In testimony whereof I have hereunto set my hand in the presence of two subscribing witnesses.

FRANK A. RYTHE.
